NATHAN J. GOODMAN

by *Alfred L. Longan ATTYS*

UNITED STATES PATENT OFFICE.

NATHAN J. GOODMAN, OF ST. LOUIS, MISSOURI.

PROTECTOR FOR LAUNDRY SHIRTS.

1,253,683.

Specification of Letters Patent. Patented Jan. 15, 1918.

Application filed August 5, 1915. Serial No. 43,876.

To all whom it may concern:

Be it known that I, NATHAN J. GOODMAN, a citizen of the United States, and resident of St. Louis, Missouri, have invented certain 5 new and useful Improvements in Protectors for Laundry Shirts, of which the following is a specification containing a full, clear, and exact description, reference being had to the accompanying drawings, forming a part 10 hereof.

My invention relates to improvements in protectors for laundry shirts, wherein a thin, transparent sheet of paper having its end margin doubled to form a casing to receive 15 a reinforce is secured along its side margins to a relatively inflexible sheet of paper of less width than the thin sheet to form an open ended tubular envelop for shirts.

20 The objects of my improvements are to construct a protector comprising a backing sheet of relatively inflexible material of the approximate dimensions of a folded and laundry shirt and a thin, transparent sheet 25 of greater width than the back having its side margins folded and adhesively secured to the rear face of the backing in a manner permitting free articulation of the side margins of the thin, transparent sheet relative 30 to the inflexible backing and to provide at at least one of the end margins of the thin sheet a casing in which is held a reinforce such as a cable, wire or string whereby to obviate tearing the thin sheet in the introduction 35 of a shirt within the protector.

My invention consists in the novel construction and arrangement of parts herein-after fully described, specifically designated in my claim and illustrated by the accompanying drawings, in which

40 Figure 1 is a front face view of the protector on a reduced scale, showing a portion of the thin transparent sheet broken away to reveal the reinforcing element;

45 Fig. 2 is a fragmental, longitudinal sectional elevation showing the reinforce for the end margin of the thin transparent sheet;

Fig. 3 is an end elevation of the protector;

Fig. 4 is a fragmental perspective taken from the front of the protector; and

55 Fig. 5 is a fragmental perspective, with parts broken away, taken from the rear of the protector.

Referring by numerals to the accompanying drawings:

6 designates the backing sheet which is of rectangular, oblong shape, and made of relatively stiff, inflexible paper, to the end 60 that it will prevent soiling a shirt by creasing or folding during handling.

The numeral 7 designates the front of the protector and is made of thin, transparent paper, in order that the pattern or style 65 of a shirt may be visible therethrough, and which conforms in shape to the backing sheet 6. This thin sheet is secured along its side margins to the backing sheet and forms therewith a tubular cover or envelop 70 into which a shirt or other article is slipped and in order to minimize tearing the thin sheet along its secured margins in the introduction of a shirt or the like between it and the backing, I form at each side 75 margin of the thin sheet a flap such as 8, which I adhesively secure to the rear face of the backing sheet and as shown in the drawing the folding lines 9 between the body of the thin sheet and its flaps are ex- 80 tended beyond and unattached to the backing, whereby said margins may articulate 85 relative to the margins of the backing upon the insertion of a shirt or the like between the thin sheet and the backing.

At at least one end margin of the thin sheet I form a casing 10, by doubling the margin over the body, insert a cable, string, wire or other reinforcing element and securing the doubled back margin by adhesion 90 to the body. This reinforced end margin extends the full width of the thin sheet and is folded and secured to the backing the same as the remaining lengths of the margins.

95 It will thus be seen that I have produced a protector for shirts, which will largely prevent soiling by folding or creasing in handling, one through which the pattern or style of shirt is visible, obviating withdrawing the shirt from the protector to determine its pattern and style, one which prevents tearing the transparent sheet at the end upon the insertion of a shirt or other article, and one which provides for articulation 100 of the side margins of the thin transparent sheet relative to the backing sheet to obviate tearing when distended by the introduction of a shirt or the like.

105 Having thus described my invention,

what I claim as new therein and desire to secure by Letters Patent of the United States therefor, is:—

In a protector for laundried shirts, a 5 backing sheet constructed relatively inflexible material of the approximate dimensions of a laundried and folded shirt, a thin, flexible sheet having dimensions in one direction greater than the dimensions of 10 said backing sheet, an integral casing formed along one margin of said thin sheet and a cord secured in said casing, said thin sheet including its casing and said cord secured

along opposite margins of said backing sheet and forming therewith a tubular protector for laundried shirts, the cord arranged to prevent tearing of the thin sheet upon the introduction of a shirt into the protectors. 15

In testimony whereof, I have signed my 20 name to this specification, in presence of two subscribing witnesses.

NATHAN J. GOODMAN.

Witnesses:

E. L. WALLACE,
R. G. CRAIG.
